UNITED STATES PATENT OFFICE.

JOHN MAYFORD, JR., OF CHICAGO, ILLINOIS.

DESIGN FOR A COMBINATION BLOTTER AND CALENDAR HOLDER.

Application filed October 12, 1925. Serial No. 15,103. Term of patent 3½ years.

To all whom it may concern:

Be it known that I, JOHN MAYFORD, Jr., a citizen of the United States, residing at Chicago, in the county of Cook and State of Illinois, have invented a new, original, and ornamental Design for a Combination Blotter and Calendar Holder, of which the following is a specification, reference being had to the accompanying drawings, forming a part thereof.

Fig. 1 is a plan view of the combination blotter and calendar holder showing my new design; and

Fig. 2 is a side elevational view thereof.

I claim:

The herein mentioned design for a combination blotter and calendar holder, as shown.

JOHN MAYFORD, JR.
